UNITED STATES PATENT OFFICE.

FRANK CHADIMA, OF CEDAR RAPIDS, IOWA.

CHURN-RECOIL STOP.

1,290,084.

Specification of Letters Patent.

Patented Jan. 7, 1919.

Application filed July 10, 1916. Serial No. 108,506.

To all whom it may concern:

Be it known that I, FRANK CHADIMA, a citizen of the United States, residing at Cedar Rapids, in the county of Linn and State 5 of Iowa, have invented certain new and useful Improvements in Churn-Recoil Stops; and I do hereby declare the following to be a full, clear, and exact description of the invention, such as will enable others skilled in 10 the art to which it appertains to make and use the same.

This invention relates to butter-working churning, and has for its object to provide an elastic lock or stop to support the churn barrel in proper position for the removal of the gathered butter.

The invention involves certain improvements in the device for this purpose shown in the patent to G. J. Kaplan, No. 863,282, issued 20 August 13, 1907, and will be fully hereinafter described and claimed, reference being had to the accompanying drawing, in which—

Figure 1 is a side elevation, showing a device embodying my invention in disengaged position. Fig. 2 is an end view of the same. Fig. 3 is a longitudinal section of the stop-post detached.

In the operation of butter-working churning 30 having an internal shelf on one side on which the butter is heaped as gathered, it is necessary to stop the churn with this shelf in convenient position for the removal of the butter. The churn-barrel is accordingly revolved 35 forward as much as desired, and commonly more, and the driving clutch disengaged. Thereupon the weight of the butter, sometimes amounting to half a ton, causes a powerful recoil in the movement of the churn-barrel, which must be caught and held 40 with the shelf of butter at the right elevation. In the practical use of a rigid stop (called a lock, in the patent above referred to) frequent breakages resulted, the dog, or 45 the ratchet, and in some cases even the leg of the churn supporting frame. This invention is designed to avoid this difficulty, by providing an elastic stop-dog or post, whereby the initial shock of the recoil is 50 absorbed, and the churn comes easily to rest.

Referring now to the drawing, the numeral 1 denotes the barrel of a churn, provided with a head 2. To this head is at-

tached a central trunnion 3 journaled in a bearing 4 of the main frame 5. To the 55 churn-head is also attached a large annular spur-gear 6 engaging suitably by gearing not shown with the driving jack-shaft 7. These parts being incidental, need no particular description.

To the web of the gear 6 is secured a short segment of ratchet 8, the teeth of which project endwise with respect to the churn. By reference to Fig. 2 it will be seen that the teeth are concavo-convex in form, in part to 65 somewhat strengthen them, but mainly to prevent the head of the post, when it engages them, from slipping sidewise, losing its hold and causing a breakage.

The post comprises a number of parts, described as follows: To the upper end of a tubular part 9 is secured, as by a rivet 10 through its shank 11, a ratchet-engaging head 12, having a laterally projecting nose 13 of a shape and size to engage the ratchet 75 between the teeth, and with its upper face curved as shown in Fig. 3 to correspond with their concavity. Inside this tube is slidably mounted a plunger 14, slotted at 15 to admit a bolt 16 passing through the tube. 80 Between the upper end of the plunger and the shank of the post-head is placed a stiff coil spring 17, which takes the first impact of the recoiling churn. The foot 18 of the plunger is pivoted at 19 to the frame-leg 20, 85 which is socketed at 21 so as to form a seat for the rounded end of the plunger, and thus take all strain from the pivot-bolt. At the outer side of this socket is a lug 22 to limit the outward swing of the post, which is a 90 little past its center of gravity. To the inner side of the post-tube is attached an adjustable set-screw 23, whose head abuts against and rides along the outer face of the gear flange 6^a, and thus holds the post in the 95 proper position to engage the ratchet teeth, instead of the end of the ratchet-plate, or other part.

To stop the churn in the desired position, the operator needs only to swing the stop-post over to the left while the churn is turning normally, clockwise as to Fig. 2. When the ratchet is passing its upper end he shifts the driving clutch 24, whereupon the post engages the ratchet and arrests the recoil. 105 In case the ratchet goes clear past the post-

head, no harm ensues, since it is caught on the recoil, and brought to rest without any serious shock.

Having thus described my invention, I claim:

In a churn-recoil stop, the combination of a ratchet segment attachable to the churn-head, and a post comprising a ratchet-engaging head, a tubular body, a plunger slid-
able therein and attachable to the churn-

frame, the plunger being slotted to receive a retaining bolt, a bolt passing through said slot, and a spring between the ratchet engaging head and the plunger.

In testimony whereof I affix my signature in presence of two witnesses.

FRANK CHADIMA.
